UNITED STATES PATENT OFFICE

111,138

DESIGN FOR A GOLF BAG

Arnold Firle, Fond du Lac, Wis.

Application June 15, 1938, Serial No. 77,853

Term of patent 7 years

To all whom it may concern:

Be it known that I, Arnold Firle, a citizen of the United States, residing at Fond du Lac, in the county of Fond du Lac and State of Wisconsin, have invented a new, original, and ornamental Design for a Golf Bag, of which the following is a specification, reference being had to the accompanying drawing, forming part thereof.

Figures 1 and 2 in the drawing are perspective views looking toward opposite sides of a golf bag, showing my new design.

A distinctive feature of my new design resides in the top and bottom of the bag being substantially oval-shaped with their longitudinal axes disposed in planes at right angles to each other.

I claim:

The ornamental design for a golf bag, as shown and described.

ARNOLD FIRLE.
